TEASEL GIG

Wilfred N. Hadley, Springfield, Vt., assignor to
 Parks and Woolson Machine Company, Springfield, Vt., a corporation

Application June 8, 1943, Serial No. 490,030

6 Claims. (Cl. 26—31)

This invention relates to teasel gigs, used for raising the nap on wool fabrics in the course of the finishing processes.

In the common form of planetary or rolling teasel gig employed at the present time, the teasels are drilled axially and mounted end to end in pairs held fast on small spindles rotatably mounted in bearings in small stands fixed to the continuous and permanent peripheral surface of the gig cylinders. The spindles are set at a slight angle obliquely to the axis of each cylinder, and are held in their stands with capacity for removal.

As the teasel burrs wear out in use, through dulling of their points and breakage of their awns, they must be replaced at periodic intervals by new burrs. Since there are two cylinders in each gig, each having more than 1500 burrs, it is a lengthy task to renew the teasels, and in addition to the loss of hours of machine time involved in this renewal, each spindle must be removed from the cylinders by hand and replaced after changing the burrs, the work being done right at the machine, and since the cylinders are surrounded by other cooperating rolls, brushes, cloth guides, and other machine parts rendering them accessible only in limited locations, it is an unpleasantly laborious and back-breaking job. It is this difficulty in keeping the napping surfaces in serviceable condition which has been largely responsible for resort to the use of napping machines employing wire card clothing in place of the older teasel gig, in spite of the admitted fact that the teasel gig produces a far better and more desirable finish on the fabric.

It is the main object of the invention to make the job of renewing the teasels on a rolling teasel gig much shorter and easier, and to this end the invention method and means consist in making the peripheral surfaces of the gig cylinders of removable slats on which the small stands holding the burr spindles are permanently mounted, whereby when the burrs become worn to an extent requiring renewal, the slat or slats carrying such burrs can be quickly and easily removed from the cylinder and replaced by other slats in which fresh teasels have already been installed in working relation. In this way, not only is the time required to renew the napping surface on each cylinder greatly reduced, with consequent large saving of machine time, but the ease and convenience of effecting the renewal is vastly increased, since the 70 to 80 new burrs on each slat are installed on the machine at once as a

unit, while the slats which are removed can be taken to a table or bench where the change of the burrs is effected with full convenience of access and facility and comfort.

5 Other objects of the invention, and the manner of their attainment, are as set forth hereinafter.

Illustrative embodiments of the invention are shown in the accompanying drawing in which

10 Fig. 1 is a view in perspective of a portion of one of the cylinders of a teasel gig, showing the removable slats of the invention and the manner of securing them to the cylinder, the burrs, spindles and stands therefor being omitted for clarity.

Fig. 2 is a face view of one of the novel slats, showing the burrs mounted on spindles rotating in stands fixed on the slat.

15 Fig. 3 is a section on line 3—3 of Fig. 1.
 Fig. 4 is a section on line 4—4 of Fig. 1.

20 In accordance with the novel method of the invention, the improved gig cylinder, instead of being formed as heretofore with a continuous cylindrical surface of wood or metal permanently attached at and intermediate its ends to heads or spiders, and with the spindle stands permanently affixed to this cylindrical surface, is composed of a plurality of spiders 1 fixed at spaced intervals on a shaft 3 journaled in suitable bearings in a machine frame (not shown), on which spiders are fastened with capacity for easy removal a plurality of slats 5, preferably of sheet metal, extending for the full length of the working surface of the cylinder parallel to its axis and disposed around the entire periphery in closely spaced relation to each other. As shown, each slat is provided at each end with a notch 7 to receive the shank of a screw 9 threaded into the face of the end spiders 1 forming the cylinder, these screws fixing the ends of the slats to their proper spider 1, while turn buttons 11 are pivotally mounted on screws 13 threaded into the intermediate spiders 15 at the intervals between adjacent slats 5 so that each may be 25 turned into a position in which its end portions overlap the edges of the adjacent slats to hold these portions of the slats closely to the faces of spiders 15. In certain instances, turn buttons 11 are used also at the ends of the slats, in place of the screws 9.

30 The usual small stands 17 are fastened by bolts 19 in a double row lengthwise throughout the full extent of the slats 5, each stand having a bearing 21 in which rotates the butt end of one spindle 23 and a second bearing 25 in which

the tip end of an adjacent spindle 23 is rotatably mounted. The usual clip 27 is also provided to support the base end of one of the pair of teasel burrs 29 fixed on each spindle. It is noted that each slat is bent slightly along its longitudinal median line, so that the two halves thereof lie in obliquely related planes intersecting along such median line, giving the slat a flat V-section. Thus, the stands 17 of each of the two rows extending lengthwise of a slat are provided with a flat surface for their attachment while each slat is made wide enough to carry two rows of stands without giving the completed cylinder any significant amount of flattened areas or departure from cylindrical periphery to impair its efficiency in bearing against the fabric.

In renewing the burrs on the improved gig cylinder, the screw 9 at one end only of each slat 5 to be removed is taken out, and turn buttons 11 retaining such slat are turned a quarter-turn, and each slat is then moved endwise slightly to free its other end from the head of screw 9 at such end, whereupon the entire slat with its worn burrs is removed as a unit. Thereupon another slat having new burrs all installed in working relation on their spindles 23 in stands 17 is put into place with one of its notches 7 under the head of one screw 9, the other screw 9 is replaced in the notch at its opposite end, and turn buttons 11 turned back into their holding position of Fig. 1. The machine is then in readiness to resume operation. The slat having the worn burrs, thus removed, is then refilled with new burrs at any convenient working place, and held in readiness for instant installation when needed.

In applying the invention to existing teasel gigs in which the cylinders have continuous cylindrical surfaces of wood or metal permanently attached to the supporting spiders, the stands 17 are simply removed from the fixed surface of the cylinder and mounted on slats 5 attached to the cylindrical surface with capacity for quick and easy removal in a manner exactly analogous to that already described, as by means of the screws 9 and turn buttons 11.

While I have illustrated and described a certain form in which the invention may be embodied, I am aware that many modifications may be made therein by any person skilled in the art, without departing from the scope of the invention as expressed in the claims. Therefore, I do not wish to be limited to the particular forms shown, or to the details of construction thereof, but what I do claim is:

1. A cylinder for a teasel gig having in com-

bination a shaft, supporting surfaces each mounted concentrically upon such shaft, slats, means for mounting teasel burrs in working relation upon such slats and in spaced relation to the slats and with capacity for rotation about the axis of such burrs, and means attaching the slats to the supporting surfaces in parallel relation to the shaft with provision for quick detachment therefrom while retaining the teasel burrs mounted in working relation upon the slats.

2. A cylinder for a teasel burr gig comprising in combination a peripheral surface composed of a plurality of slats, a shaft, supporting means on such shaft holding the slats in parallel relation to such shaft and in equidistant spaced relation therefrom, spindles and bearings on the slats rotatably supporting teasel burrs, and quickly releasable fastening means securing the slats to the slat-supporting means with capacity for easy removal of the slats for renewal of the teasel burrs.

3. A cylinder for a teasel gig having in combination a shaft, spiders fixed on such shaft, slats on such spiders in parallel relation to such shaft, stands on such slats, spindles rotatably mounted in such stands, and teasel burrs mounted on such spindles, the slats being quickly and individually removable from the spiders for renewal of the teasel burrs.

4. A cylinder for a teasel gig having in combination a shaft, spiders fixed on such shaft, teasel burrs, stands and spindles rotatably supporting the teasel burrs, and a plurality of elements mounted on the spiders and forming the periphery of the cylinder and on which the stands are fixed, such elements being quickly detachable and removable from the spiders and carrying with them upon removal the stands fixed thereon together with the spindles and teasel burrs supported thereby.

5. A slat for a teasel gig cylinder comprising in combination a metal strip bent into flat V-section, stands fixed on the outer surface of the strip at each side of the bend, spindles rotatably mounted in such stands, and teasel burrs mounted on the spindles.

6. In a teasel gig, in combination, a cylinder comprising a shaft, spiders fixed thereon, slats having notches at their ends, stands on the slats, spindles rotatably mounted in the stands, teasel burrs on the spindles, and fastening means on the spiders engaging in the notches on the slats and holding the latter in working position with capacity for quick and easy release to permit removal and replacement of the slats.

WILFRED N. HADLEY.
